UNITED STATES PATENT OFFICE

WILLIAM F. KIESEL, JR., OF ALTOONA, PENNSYLVANIA

RAILWAY DRAFT GEAR

Application filed September 9, 1926. Serial No. 134,527.

This invention relates to railway draft appliances and more particularly to the provision of means on a vehicle for the reception, in a longitudinal direction, of a 15 double acting draft gear, draft yoke, coupler butt and associated parts.

It is a general object of the present invention to provide a novel and improved type of draft appliance adapted to be used 10 at the front end of locomotives and on tenders and cars.

More particularly it is an object of this invention to provide a draft casting having a draft assembly pocket open at the end 15 for the reception of a friction draft gear, a draft yoke, followers and a coupler butt, removable means being provided to retain said assembly in position in the pocket and to take the draw bar pull.

20 A further object of the present invention consists in the provision of a draft pocket casting having formed integral therewith rear stops, said pocket being open at the outer end for the reception of a single, 25 double acting friction draft gear, a follower, a draft yoke and a coupler butt, said coupler butt and draft yoke being pivoted together, keys being provided to be removably positioned against said follower to retain 30 the draft assembly in the pocket, said keys being substantially in alignment with the 35 pivotal connection between the draft yoke and the coupler butt, there being means provided to retain the coupler head in central position.

40 A still further object of the present invention consists in the provision of a draft assembly pocket having an open end of a size sufficient to receive therethrough the whole draft assembly, said end being provided 45 with adjustable filler blocks to support the draw bar which is less in cross sectional area than said opening.

45 Other and further objects of the present invention will be more apparent to those skilled in the art after a consideration of the following specification and accompanying drawings wherein are disclosed two exemplary embodiments of the invention with 50 the understanding, however, that various

and sundry changes may be made therein without departing from the spirit of the invention or the scope of the appended claims.

In said drawings:

Fig. 1 is a top plan view partially in horizontal section of the present invention shown as applied to the front end of a locomotive; 55

Fig. 2 is a central longitudinal vertical section of Fig. 1; 60

Fig. 3 is a transverse section on line 3-3 of Fig. 1;

Fig. 4 is a transverse section on line 4-4 of Fig. 1 showing a portion of the adjusting blocks broken away; 65

Fig. 5 is a plan view of the rear end of a tender showing the invention applied thereto; and

Fig. 6 is a side elevation of Fig. 5 showing portions broken away for the sake of 70 clearness.

The customary arrangement of draft mechanism for railway vehicles comprises a pocket formed in or near the end of the car in a sill or buffer and having an open 75 bottom into which the draft gear, draft yoke and other parts may be lifted and held in place by a pan or strap which takes the weight of the draft assembly.

The front and back stops for the draft gear are usually 80 solidly attached to the part in which the pocket is formed and there is provided a coupler carrier iron to support the outer end of the coupler. The casting being open at the bottom, is weak and buffing and pulling strains tend to break it, as well as to

force the strap or pan out of position. The present invention overcomes the above difficulties by providing a pocket for the reception of the draft appliances which is closed 85 at the bottom and open only at the outer end. Through this opening the entire assembly is adapted to be placed in the pocket after which a pair of keys is positioned to cooperate with the front follower 90 and retain the whole assembly in the pocket.

Suitable adjustable filler blocks close portions of the open end of the pocket and serve to adjustably support the coupler head 95 at the proper elevation above the track. 100

Referring to the drawings, and particularly to Figs. 1 to 4 inclusive, wherein is shown an embodiment of the invention adapted to be applied to the front end of locomotives, there is disclosed at 10 what may be termed the front end casting of the locomotive adapted to be secured, by any suitable fastening means, between the side frames 11 and 12. The end 13 of the casting is closed with the exception of the central portion 10 wherein is provided the opening 14 leading to the draft gear pocket 15 within the casting. This pocket is formed by the top plate 16 which is substantially flat and the bottom plate 17 which is also substantially flat. 15 The side walls 18 of the pocket converge slightly from the opening 14 and then become parallel until they reach a position near the rear of the casting where they are offset toward each other forming the shoulders 19 which are the draft gear rear stops. The walls then continue rearwardly for a short distance parallel to each other. The top plate 16 extends from side frame to side frame at the front and has its edges converging 20 toward the rear. The bottom plate is of the same shape and the two converging edges are secured together by vertical walls 20 suitably reinforced by webs as shown. The top wall is provided at 21 with perforated 25 bosses whereby it is adapted to be bolted to the under surface of the cylinder saddle of the locomotive.

The rear portion of the pocket 15 is of a size to snugly receive a suitable double-acting, friction draft gear 22 which abuts against the draft gear rear stops 19 previously described. The front follower 23 is likewise of such a size as to fit snugly but 30 with freedom of movement in the pocket. 35 The function of the draft gear and follower plate and their operation are too well known to need description here. Encircling the draft gear longitudinally is the draft yoke 24 working in suitable channels formed in the top and bottom plates by offsets toward the front of the pocket and being freed at the rear by means of the cutouts 25 and 26 in the top and bottom plates respectively. 40 45 This draft yoke is of the type described in the patent to Harry A. Hoke No. 1,213,196, patented January 23, 1917, and has provided, in addition to the yoke strap, the hollow metal member 27 which is widened 50 at the ends into a spade form so that it substantially touches the side walls of the pocket to prevent the yoke from having lateral movement at its forward end, the rear end being restricted where it passes between the narrowed portions of the walls 18. This 55 hollow member 27 is securely riveted to the front end of the yoke strap as shown and near the rear of the hollow member a suitable vertical opening passes through both 60 the hollow member and the yoke strap which

opening is adapted to receive the yoke pin 28 having its head seated in a counterbore in the yoke strap. This yoke pin serves to connect the yoke with the coupler butt 29, to the forward end of which is secured the coupler head 30 of any conventional form. 70 For this purpose the rear end of the coupler butt is thickened and drilled to receive the yoke pin 28. The metal of the coupler butt end is not only thickened to increase the bearing area of the yoke pin, but it is widened and provided with a flat rear end as shown at 31. This flat rear end abuts the front face of the front follower 23. Since the rear of the yoke strap is abutted by the rear of the draft gear, it follows that the front follower will be pressed tightly against the flat rear end 31 of the coupler butt, which is pivoted to the yoke by the yoke pin 28 forward of the abutting faces 31 and the front follower. By this means the springs of the draft gear cause the yoke and the coupler butt to maintain an alignment or to return to alignment after they have been displaced.

The draft assembly, as the draft gear, draft yoke and coupler butt may be termed, is adapted to be inserted into the pocket 15 through the open end 14 thereof when the parts of the draft assembly are assembled as a unit. To retain them in the pocket and to provide means to take the pull of the coupler, keys are provided which pass through the top and bottom plates of the casting and engage against the front of the front follower, beside the coupler butt.

In Figs. 1, 2 and 3 these keys 32 are adapted to be inserted from the top where they are readily accessible through the pilot of the locomotive. They are rectangular in form, pass through the top and bottom walls 16 and 17 and are partially housed in offset channels 33 in the pocket walls 18. These keys have enlarged heads 34 to prevent them from falling through the casting and are retained in position by the split keys 35 passing through suitable slots 36 therein and engaging against the bottom wall 17 of the casting. The keys are placed in position after the draft assembly is in the pocket and serve to take the full strain of the draw bar. Buffing is taken by the draft gear rear stops 19 cast integral with the pocket. It will be noted that the coupler butt is much less in cross sectional area than the pocket opening, and hence can have movement to the right and left to accommodate slight misalignment of the cars and to take care of any turning movement of the cars. It is pivoted to the draft yoke substantially in alignment with the two keys 32 so that it has freedom of side-wise movement without affecting the yoke or causing any binding of the yoke in the pocket. This effect is further enhanced by 130

having the yoke extend forwardly of the pin and have its spade end guided by the walls 18 of the pocket.

To support the coupler at the proper elevation and to partially close the end of the pocket, the end block 37 and the draw bar carrier block 38 are provided against the top and bottom walls respectively at the mouth of the pocket. They are held in position by suitable bolts 39 which have their heads recessed in the blocks and are provided with nuts on the outside of the casting. In order to take care of sagging of the locomotive due to settling of the springs and to other causes, means are provided for blocking up the draw bar in order that it may always remain at the proper elevation for coupling purposes. Such means comprises two or more shims 40 which are initially arranged above the end block 37 in order to retain the space between the end block and the draw bar carrier always the same. As the locomotive sags, one or more of the shims are removed from the position shown and are arranged beneath the draw bar carrier. These blocks, in addition to supporting and guiding the draw bar, serve as a secondary means to retain the draft gear in the pocket in case the keys are damaged or removed inadvertently.

The draft arrangement just described is particularly adapted for the front end of locomotives, but the invention is not limited to that use. In Figs. 5 and 6 is shown a means for applying the invention to the rear end of a locomotive tender such as that described in the applicant's copending application Serial No. 77,567, filed December 24, 1925, although it need not be limited to that particular type of tender underframe.

In Figs. 5 and 6 there is disclosed the rear end of a tender frame having a single central sill 50 formed as a casting provided with the integral short bolster 51. A suitable buffer beam 52 is secured to the upper surface of the sill casting by means of the gusset plate 53 inset into the casting as shown and extending to the ends of the buffer beam. The beam is formed of two channel members 54 having a suitable top plate thereon. The end of the sill has provided therein a pocket of substantially the form disclosed in the modification previously described, but the top of this pocket is, in the casting, open. It is, however, closed by the gusset plate 53 as clearly shown in the drawings, thus forming a pocket substantially identical with that previously described and having substantially flat top and bottom walls which, together with the side walls, completely enclose it. Since the tender tank and other parts cover the gusset, the keys 55 are inserted from the bottom and pass upwardly into the top wall of the casting as in the previous modifica-

tion and are received in similar channels in the side walls. The keys are retained in position by a transverse bolt 56 which passes through suitable holes near the bottom ends of the keys and through a pair of depending lugs 57 integral with the casting. A nut 58 and suitable locking means are provided to retain the bolt in position.

The remaining portions of the device as applied to a tender are the same as those used in conjunction with the locomotive modification and the operation is the same. It will readily be apparent to those skilled in the art how the device may be applied to any form of railway car where it may be so desired, and it is intended that the claims appended hereto shall be construed as applied to any form of railway vehicle.

Having thus described the invention, what is claimed as new and desired to be secured by Letters Patent is:

1. In a device of the class described, in combination, a complete draft assembly including a single draft gear, front and rear followers, a draft yoke and a coupler including shank and butt, a pocket casting adapted to be attached to a vehicle and having an open end larger than said coupler shank, said draft assembly being adapted to be placed in said pocket through said open end while completely assembled, means pivotally securing said yoke to said coupler butt near the front end of said yoke and ahead of said draft gear, keys passing through the top and bottom of said pocket casting and positioned to engage the front follower to retain the draft assembly in said pocket and to take the coupler pull, said keys being substantially adjacent the connecting means for said yoke and coupler butt, and an adjustable coupler shank carrier secured to said casting at the mouth of said pocket.

2. In a vehicle, in combination, a frame, a casting secured to said frame and having a draft assembly pocket therein, said pocket opening at the end only and having substantially flat top and bottom walls, a pair of draft gear rear stops integral with said casting, a coupler having a butt smaller in cross section than the pocket opening, a draft yoke pivoted to said coupler butt, a single, double-acting draft gear within said yoke, a front follower for said draft gear, said coupler butt having a flat rear end behind its pivot, said follower and rear end being pressed into engagement by said draft gear to always return the yoke and coupler to alignment, said draft gear, draft yoke, follower and coupler being adapted to be completely assembled and then introduced into said pocket through the end opening with the draft gear against said rear stops, keys adapted to be introduced through said top and bottom walls to engage said fol-

lower to retain said assembly in said pocket, said pivotal connection between said draft yoke and coupler butt being in substantial alignment with said keys, and a substantial

5 distance within said pocket, and end blocks secured to said casting above and below said coupler shank to partially close the pocket opening.

3. In a railway vehicle, in combination, a
10 frame, a casting secured to said frame and substantially at the end of the vehicle, said casting having a pocket therein opening toward the end of the vehicle, the side, top and bottom walls of said pocket being substantially flat, a draft gear rear stop in said pocket, a draft assembly including a single double-acting draft gear, a draft yoke surrounding said gear, a front follower, a coupler having its butt pivoted to said yoke and
15 its end engaging said follower, means on said yoke near the coupler butt to retain said yoke in alignment in said pocket, said coupler butt being of such a size as to have freedom of movement in the mouth of said
20 pocket, the whole draft assembly being adapted to be placed in the pocket as a unit, a key adapted to pass through said casting and engage said follower to retain the assembly in the pocket, and filler blocks se-
25 cured to said casting above and below said coupler butt for the purpose described.

4. Draft gear structure comprising laterally spaced draft beam members, a hollow casting secured between the forward ends
30 of said beam members, a yoke disposed between said beam members, a follower plate extending through said yoke, laterally spaced abutments on the interior of said casting, removable locking keys disposed
35 between said abutments and said follower plate, and a removable coupler shank guide on said casting.

5. Draft gear structure comprising laterally spaced draft beam members, a hollow casting secured between the forward ends of said beam members, a yoke disposed between said beam members, a follower plate extending through said yoke, laterally spaced abutments on the interior of said casting, removable locking pins disposed between said abutments and said follower plate, and a member removably mounted at the front of said casting and partially closing the open end thereof.

55 6. Draft gear structure comprising laterally spaced draft beam members, a hollow casting secured between the forward ends of said beam members, a yoke disposed between said beam members, a follower plate extending through said yoke, laterally spaced abutments on the interior of said castings, removable locking keys disposed between said abutments and said follower plate, and a member mounted at the front of said
60 casting and partially closing the open end

thereof, the said member being positioned to afford vertical support to a coupler shank.

In testimony whereof I hereunto affix my signature.

WILLIAM F. KIESEL, JR.
